UNITED STATES PATENT OFFICE.

WILLIAM ROBERTS AND DELLFORD H. HOLLOWAY, OF WATERFORD, NEW YORK, ASSIGNEES
OF ONE-THIRD TO CHARLES W. SCOVILLE, OF COHOES, NEW YORK.

DAMPER-REGULATOR.

No. 904,894.

Specification of Letters Patent. Patented Nov. 24, 1908.

Application filed September 11, 1907. Serial No. 392,268.

To all whom it may concern:

Be it known that we, WILLIAM ROBERTS, a citizen of the United States, residing at Waterford, in the county of Saratoga and State of New York, and DELLFORD H. HOLLOWAY, a citizen of the United States, residing at Waterford, in the county of Saratoga and State of New York, have invented certain new and useful Improvements in Damper-Regulators, of which the following is a specification.

This invention relates to damper regulators, and has for an object to provide improved mechanism for opening a damper upon the fall of steam pressure to a certain predetermined point, and for closing the damper upon the rise of the steam pressure to another predetermined point. By this improvement electrical contacts may be so individually adjusted that the damper will be opened and closed by the fall and rise of the steam of a certain predetermined number of pounds, and then these adjusted electrical contacts may be so adjusted that the damper will be closed at the rise of the steam to a certain pressure, the limit of fall of pressure for opening the damper having been previously fixed by the individual adjustment of the contacts.

If the engineer desires to employ steam sometimes at one pressure and sometimes at another but to maintain a substantially constant pressure; that is if he only desires to have a fluctuation say of two pounds, but sometimes desires to have twenty pounds of steam and sometimes desires to have one hundred pounds of steam, the electrical contacts will be so adjusted that a contact carried by the pressure gage, as for instance a Bourdon tube, will make contact with one of these upon a rise of two pounds pressure over the pressure required to make the contact with the other, and then by bodily adjusting these contacts which have been set, they can be placed in a position where they will control the damper upon these predetermined fluctuations, which take place about the predetermined desired pressure. The engineer might desire to run his engine with one hundred pounds of steam at the boiler, and want to keep it just at one hundred pounds. The electrical contacts would then be so adjusted that the damper would be closed when the pressure got one-half pound above the one hundred pounds and will be

opened when the pressure falls half a pound below one hundred. And then when the fires are banked and the factory is shut up for the night or a holiday, he may desire to have the steam at the boiler at twenty pounds for heating purposes; and without changing the amplitude of movement of the contact carried by the pressure gage, he will merely adjust the contacts bodily to get his twenty pounds pressure and have the same damper action upon the same rise and fall as in the other instance.

In the drawings accompanying and forming a part of this specification, Figure 1 shows a practicable embodiment of a form of our invention applied to a boiler. Fig. 2 is an enlarged view of the gage and contact portions of the invention showing the front portion of the casing cut-off on a vertical plane. Fig. 3 is an edge view of the contact devices. This view is enlarged more than is Fig. 2. Fig. 4 is a detail upon the same scale as is Fig. 3 showing certain parts which will be described in detail in the proper place; and Fig. 5 is a vertical section through the contacts of the motor.

In Fig. 1, the boiler is designated in a general way by 7 and is provided with a dome 8 and a chimney flue 9, which chimney flue is provided with a damper, shown in dotted lines at 10, to which damper is attached a lever 11 provided with a weight 12. The lever 11 is connected to a rotary arm 13 of a motor 14 by a suitable connection 15. This motor 14 is of a type which is now upon the market and is frequently used. Its construction is such that the arm 13 will, upon the closing of an electrical circuit, be given a half revolution and will be stopped, and upon the closing of another electrical circuit, will be permitted to make another half rotation. Since it is of the well known type, and since other motors for performing the same work could be employed in this connection, we will not enter into further detail concerning its construction and actuation, except to say that in Fig. 1 the damper is shown in an open position and the arm 13 in its upper position, where it will be automatically stopped until the circuit is closed for closing the damper when it will be turned to its lower position and there held until the circuit is closed for opening the damper.

An electrical battery is illustrated in a

conventional way at 16; and a wire 17 leads from the battery to an electro-magnet 18 for controlling the motor 14, a wire 19 grounds the magnet on the frame 20 of the motor, 5 wires 21 and 22 are carried to insulated contacts 210 and 220 on the motor frame and the circuit to the frame is completed by a brush 132 carried by a wheel 131 fast on the shaft 130 of the arm 13. A wire 23 10 grounds the battery 16 on the regulator frame plate 24.

The regulator is shown as having a carriage 25 carried by an arm 26 pivoted at 27 to the frame plate 24, an arm 28 is pivoted 15 to the carriage at 29, this arm constitutes a pointer for coöperation with a scale 30. The arm 28 is also pivoted to the plate 24 by means of a screw 31, passing through a slot 32 in the carriage 25.

20 The movement of the carriage, its oscillation in the present instance about the axis 27, is effected by means of a set screw 33 having one end stepped in a bearing 34 carried by an arm 35 from the plate 24. This set or 25 carriage-adjusting screw passes through a nut 36 mounted on the carriage. The movement of the end of the pointer adjacent the scale will be relatively long, compared with the movement of the carriage on account of 30 the leverage.

The carriage has upon it two posts 37 and 38 which are insulated from it and to which are respectively connected, by binding screws 39 and 40, the wires 21 and 22. These posts 35 carry adjustable electrical contacts 41 and 42 respectively, these contacts are shown in the form of screws, with enlarged shanks 43—44 carrying scales 45—46 coöperative with index pointers 47—48 carried by the 40 carriage.

The boiler dome 8 is shown connected by a pipe 50 with the movable member of the regulator, in the present showing a Bourdon tube 51, which has fastened to its free end 45 an electrical contact 52 which, upon rise of pressure will engage the contact 41 and close the circuit comprising the battery 16, wire 23, plate 24, Bourdon tube 51, contact 52, contact 41, post 37, wire 21, contact 210, 50 brush 132 and frame 20 of motor, wire 19, magnet 18, wire 17 to battery. The closing of this circuit will cause the motor arm 13 to move down and close the damper, and upon the fall or reduction of pressure, the 55 Bourdon tube will return toward its normal position and will bring the contact 52 into engagement with the contact 42 and will close the circuit of wire 22 and actuate the motor to raise the arm 13 to the position 60 seen in Fig. 1 and which will cause the damper to open. The contact 42 will be adjusted to the proper position, so that the contact 52 will engage it when the boiler

pressure, as indicated at the gage 49 for instance, corresponds to the reading of the 65 scale 30 and pointer 28. The contact 42 may then be locked in its adjusted position by a set nut 53, when it is now desired that the damper be opened when the pressure falls below a certain number of pounds, the 70 carriage 25 will be moved until the pointer indicates the number on the scale 30, fifty 75 for instance. The damper will be kept open until, not only has the contact 52 been moved away from the contact 42 but also until it has reached the contact 41 when the proper 80 circuit will be closed for closing the damper. The amount of pressure above the damper opening pressure which will be permitted before the damper is closed will be determined by the position to which the contact 41 is adjusted, and where this is once fixed it may be permitted to so remain, irrespective of adjustments for the damper opening pressure.

Having thus described our invention, we 85 claim:

The combination with a steam boiler and a furnace for heating the same, said furnace being provided with a smoke stack and 90 damper, of a Bourdon tube open to the boiler and responsive to rise and fall of boiler pressure, an electric contact carried by the free end of the Bourdon tube, an electrically controlled damper operating device constructed and adapted, upon the closing of an electric circuit, for moving to open the damper and to remain in the damper opening position until actuated to close the damper, and, upon the closing of an electrical circuit, for moving to close the damper and remain in the damper closing position until moved to open the damper and electrical connections between said damper operating device and the tube contact, a carriage adjustable along a path parallel with the path of movement of the tube contact, an adjustable electrical contact upon said carriage for the engagement of the tube contact upon the movement of the tube incident to 100 rise in boiler pressure and means for electrically connecting this adjustable contact with the damper operating device for effecting the closing of the damper, and an adjustable electrical contact upon the carriage 105 for the engagement of the tube contact upon the movement of the tube incident to fall in boiler pressure and means for electrically connecting this adjustable contact with the damper operating device for effecting the 110 opening of the damper.
